UNITED STATES PATENT OFFICE.

VIRGIL BALLOU, OF DES MOINES, IOWA.

FURNACE.

Application filed December 24, 1925. Serial No. 77,486.

This invention relates to improvements in furnaces, and more particularly to that type which is employed for heating houses, and may be used with either hot water or steam heating systems.

The object of my invention is to provide a furnace of simple, durable and inexpensive construction, which may be easily and quickly installed.

10 A further object is to provide a furnace of the steam or hot water type which may be easily handled by being formed with a base section and a boiler section and a cap section, the base section including the grate, 15 ash pit and a portion of the fire pot, while the boiler section is formed in a separate unit and designed to rest on top of the base section and includes a portion of the fire pot.

A further object is to provide in a furnace simple and inexpensive means whereby combustion will be completed when the furnace is in operation, to reduce the amount of soot and similar carbonaceous substances which usually gather on the inner face of 25 the flue and require constant cleaning.

A further object is to provide in a furnace an improved fire pot whereby a lining of heat insulating material may be easily and quickly removed or replaced.

30 My invention consists in the construction, arrangement and combination of the various parts of the device, whereby the objects contemplated are attained, as hereinafter more fully set forth, pointed out in my 35 claims, and illustrated in the accompanying drawings, in which:

Figure 1 is a vertical sectional view of my improved furnace.

Figure 2 is a transverse sectional view 40 taken on the line 2—2 of Figure 1.

Figure 3 is a segmental, detail, sectional view taken on the line 3—3 of Figure 1.

Figure 4 is a detail sectional view taken 45 on the line 4—4 of Figure 1.

Figure 5 is a detail sectional view taken on the line 5—5 of Figure 2.

50 My improved furnace comprises a base section 10 formed cylindrical and of cast metal, said base having its inner face provided with an inwardly projecting rib 11 about midway between its bottom and top. Said rib and the member 10 are provided with a series of inwardly projecting brackets 12, each of said brackets having at its upper

edge a notch 13. Said notches 13 are designed to receive a ring member 14 in which the grate members 15 are pivotally mounted in the usual manner. The member 14 is preferably formed of two pieces having their adjacent ends joined together by means of 55 bolts 16. Said member 14 is provided with an upwardly extending rib 17. The member 14 and the top of the rib 11 are in a common horizontal plane. The outer edge of the member 14 and the rib 11 provide means 60 for supporting a tier of fire brick 18 adjacent to the inner face of the base member 10, clearly illustrated in Figure 1.

The upper edge of the base member 10 is provided with an inwardly extending flange 70 portion 19 which rests above the top edge of the brick lining 18. The width of the flange 19 is substantially equal to the thickness of the lining wall of the member 10.

One side of the member 10 is provided with a clinker door 20 and an ash and draft door 21. The inner edge of the member 19 is designed to support a boiler portion 22 which is also formed cylindrical and having a bottom plate 23 and a top plate 24. 80

The bottom plate 23 is provided with an opening 25 which is of considerable size and placed eccentrically with the outer cylinder wall 22. The said opening 25 is designed to receive an upwardly extending tubular 85 member 26 having a top plate 27. One side of the member 26 is provided with a door casing 28 which extends through both the outer wall 22 and the tubular member 26, said casing being located at the upper end 90

of the member 26, as clearly shown in Figure 1. The top plate 24 is provided with an opening 29 arranged vertically above the opening 25. The opening 29 is provided with an upwardly extending tubular member 30 having a top head member 31. The head members 23 and 24 are provided with a series of vertical flues 32, the lower ends of which communicate with the interior of the base 10, while the upper ends communicate with a hot air chamber 33 formed by means of a cylindrical cap 34 designed to rest on top of the member 22 in a detachable manner.

The said cap 34 is provided with detachable top plates 35, said plates being a slight distance above the top of the head member 31. A horizontally arranged baffle plate 36

is provided which is formed preferably of two pieces, as clearly shown in Figure 2, to divide the chamber 33 into upper and lower compartments. The upper compartment is 5 provided with a stack opening 37. Suitable outlet pipes 38 may be provided in the head 31, while inlet pipes 39 are mounted in the lower end of the boiler member 22.

By this construction it will be seen that 10 the lower end of the cylindrical member 26 is in communication with the fire pot and that the door casing 28 is located a considerable distance above said fire pot.

In actual operation, the fuel is delivered 15 through the door casing 28 and to the grate bars 15 in such a manner that the member 26 serves as a magazine for feeding fuel to the grate, said magazine being partially or wholly filled. The top surface of the fuel is 20 inclined downwardly and rearwardly from the back side of the lower end of the member 26, so that a combustion chamber 40 is provided beneath the end of the flues 32. The heated gases will be drawn upwardly 25 through the said flues and into the lower chamber 33 and around the shell 30 and over the front edges of the baffle plate 36 and into the smoke stack. The boiler may be filled to a point slightly above the head 24, 30 if it is desired to be used for steam heating, in which case the member 30 serves the purpose of a steam dome. The heated gases passing around the outer surface of said dome serve to dry the steam to a certain extent, so that nothing but dry steam is fed to 35 the radiators, and thereby reducing the amount of water returned from condensation.

By placing the magazine member 26 near 40 the front side of the fire pot, it will be seen that the fuel will be piled adjacent to the side above the draft or opening 21, and that the bottom of the pile of fuel will become intensely heated and the lower end of the 45 pile of fuel in the magazine 26 will become heated and the gases will be drawn downwardly through the heated fuel in the fire pot. A certain amount of draft is permitted to enter through the door opening 28. By 50 this method the carbon of the gases will be consumed before the products of combustion reach the vertical flues 32, and thereby eliminate any carbonaceous deposits on the inner surface of said flues, and eliminating the necessity of having to clean the same. On account of the flues being vertical, any ashes or similar material will be drawn upwardly 55 through the flues or will settle back on the grates. Any material being drawn upwardly will be deposited on the upper face of the plates 24 and 36 where it can be easily removed through suitable cleanout doors 41.

By providing the ring 17 and the inwardly projecting flange 11, I have provided 60 means whereby the interior of the fire pot

may be easily and quickly lined with fire-proof material such as brick. The ring member 17 is formed in sections which are bolted together, and which performs the function of supporting the lining as well as 70 the grate bars, said ring being adapted to be easily and quickly renewed in case it is burned out or becomes warped. The exterior surface of the members 22 and 34 may be covered with a thick layer of heat insulating material 42, said material being of a thickness substantially equal to the width of the member 19, so that the finished furnace has a cylindrical formation and is compact 75 and neat in appearance.

If the flues 32 should become foul after being in use for some length of time, they may be easily and quickly cleaned by simply removing the cover plates 35 and the baffle plates 36, which are detachably secured in 80 position by means of suitable bolts 43.

Thus it will be seen I have provided a furnace of simple, durable and inexpensive construction, which may be used equally well with either hot water or steam heating systems, and which is very compact when assembled and easy to handle while being erected, due to the fact that it is formed in three sections which are assembled by simply placing one section on top of the other. 95

I claim as my invention:

1. A furnace comprising a base member including a fire pot, a boiler member detachably mounted above said base member, said boiler member being provided with a vertically arranged magazine having its lower end communicating with the top of the chamber within said fire pot and its top end closed, said magazine being eccentrically mounted within said fire pot and provided with a fuel opening near its upper end, the space between said magazine and the vertical walls of said boiler being provided with vertically arranged flues, a cap member on the upper end of said boiler, and a steam dome for said boiler and arranged eccentrically in said cap and directly above said magazine, said cap member having horizontally arranged baffle plates mounted in the larger portion of the space between said dome and the inner wall of said cap, said cap being provided with a flue opening above said baffle plates. 105

2. A furnace comprising a base member including a fire pot, a boiler member detachably mounted above said base member, said boiler member being provided with a vertically arranged magazine having its lower end communicating with the top of the chamber within said fire pot, said magazine being eccentrically mounted within said fire pot and provided with a fuel opening near its upper end, the space between said magazine and the vertical walls of said boiler being provided with vertically arranged flues, 115

a cap member on the upper end of said boiler, and a steam dome for said boiler and arranged eccentrically in said cap and directly above said magazine, said cap member having horizontally arranged baffle plates mounted in the larger portion of the space between said dome and the inner wall of said cap, said cap being provided with a

flue opening above said baffle plate, said baffle plates extending substantially half way 10 around the dome to provide passages between the dome and the walls of the cap to communicate the upper and lower compartments formed by said baffle plates.

Des Moines, Iowa, September 16, 1925.

VIRGIL BALLOU.
